TIE

David Sobel, Brooklyn, N. Y.

Application February 9, 1938, Serial No. 189,519

2 Claims. (Cl. 2—146)

This invention relates to new and useful improvements in a tie.

More specifically, the invention proposes the construction of a tie which will not stretch and which will have sufficient body regardless of whether or not a lining is applied thereto.

Still further it is proposed to provide "Zipper" or the like fasteners for closing the adjacent edges of the casing of the tie and for giving the tie sufficient body to assist in properly forming a knot, and which will hold the knot in position after the tie has been knotted.

Still further it is proposed to construct the tie in such a manner that the fasteners may be separated to permit the lining and casing of the tie to be easily ironed and straightened out.

Still further it is proposed to provide stitches between the adjacent edges of the casing of the tie for holding the free edges in position, and provide fasteners above the stitches merely for adding body to the tie.

Still further it is proposed to removably mount the lining within the tie so that the tie may be worn with or without the lining as desired.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a rear elevational view of a tie constructed according to this invention.

Fig. 2 is an enlarged detailed view of a portion of a tie with the parts in the open position.

Fig. 3 is a sectional perspective view on the line 3—3 of Fig. 2.

Fig. 4 is a view similar to Fig. 3 but illustrating a modification of the invention.

Fig. 5 is a rear elevational view of a portion of the tie illustrating a still further modification.

Fig. 6 is a sectional view on the line 6—6 of Fig. 5.

Fig. 7 is a view similar to Fig. 5 but illustrating a still further modification of the invention.

Fig. 8 is a sectional view on the line 8—8 of Fig. 7.

The tie according to this invention comprises a strip of casing material 10 adapted to be folded into a tie casing. A stringer of hook fasteners 11 of the slide control type ("Zipper" type) is secured along each edge of the casing material 10 and a strip of lining material 12 is secured along one edge of the casing 10 and over its stringer 11.

A control slide 13 is associated with the stringer of the hook fastener for closing these fasteners for holding the tie casing in its folded condition.

The strip of casing material 10 is of conventional construction and is adapted to have its edges 10^a bent inwards for forming a conventional tie. The stringer of hook fasteners comprises a cloth strip 11^a which has one of its edges fixedly secured to the edge portion of the bent in edge 10^a of the tie 10. A plurality of hook fasteners' elements 11^b are mounted upon the free edge of the stringer 11 and the hook fasteners on either side of the tie casing 10^a are adapted to be engaged with each other by means of the control slide 13 for holding the tie in its folded condition.

Stitches 14 are used for holding the edges of the cloth strip 11^a on the tie casing 10. The strip of lining material 12 is of conventional construction and is attached intermediate of its edges to one of the bent in edges 10^a of the tie casing by means of the same stitches 14 which hold the cloth strip 11^a upon the casing 10. After the slide fasteners 11^b and the lining material 12^a have been properly positioned upon the edge portions 10^a of the tie casing 10 the control slide 13 is moved from the open to the closed position for engaging the adjacent slide fasteners 11^b for holding the tie in the folded condition. In addition to holding the tie in its folded condition the slide fasteners add body to the tie which will assist in holding and shaping the knot after it has been tied in the conventional manner.

According to the modification shown in Fig. 4 the lining material 12' is removably attached to one of the edge portions 10^a of the tie casing 10 instead of fixedly attached as in the previous form. This releasable holding means comprises snap fastener elements 15^a attached to the lining material 12' and which are adapted to be engaged upon complementary snap fastener elements 16 attached to the cloth strip 11^a of the stringer of hook fasteners 11. With this form of the invention the tie may be worn with or without the lining material 12', as desired. If it is felt that the string of hook fasteners do not add sufficient body to the tie casing 10 the lining material 12' may be positioned therein, or if the tie casing 10 is too stiff with the addition of the lining material 12' this lining material may be removed by disengaging the snap fastener elements 15 and 16.

According to the modification shown in Figs. 5 and 6 a strip of casing material 20 has its edge portions 20^a folded inwards to form a tie casing.

The adjacent edges of the edge portions 20^a are fixedly attached together by means of stitches 21 and stringers of hook fasteners 22 are attached to the rear edge of the tie casing 20 merely for adding body thereto. This stringer of hook fasteners comprises a cloth strip 22^a which has one of its edges secured to an edge portion 20^a of the tie casing 20 by means of stitches 23. Hook fastener elements 22^b are attached to the free end 10 of the cloth strip 22 and these hook fastener elements 22 are adapted to be engaged with each other by a control slide 24 for assisting the stitches 21 in properly holding the tie casing in its folded condition and for adding body to the tie. According to the modification shown in Figs. 7 and 8 the tie casing 20 has its edges 20^a bent upon itself and the adjacent edges of these edge portions are secured together by means of stitches 21. One stringer of hook fasteners 22' is securely 20 attached to one of the edge portions 21^a of the tie casing 20 by means of stitches 23. The hook fastener elements 22^b which are attached to the cloth strip 22^a and merely add body to the tie casing 20. In other respects this form of the invention is similar to the previous forms.

While I have illustrated and described the preferred embodiments of my invention, it is to be understood that I do not limit myself to the precise constructions herein disclosed and the right 30 is reserved to all changes and modifications coming within the scope of the invention as defined in the appended claims.

Having thus described my invention, what I claim as new, and desire to secure by United States Letters Patent is:

1. A tie, comprising a strip of material folded into a tie casing, stitches between the adjacent edges of said strip for holding said strip in its folded condition, stringers of hook fasteners mounted longitudinally along the center of the back of said tie over said stitches for hiding said stitches from view and for adding stiffness to 10 said tie, and a control slide for opening and closing said slide fasteners, whereby said slide may be moved to close said fasteners for giving said tie one stiffness and said slide may be moved to open said fasteners to give said tie another stiffness. 15

2. A tie, comprising a strip of material folded into a tie casing, stitches between the adjacent edges of said strip for holding said strip in its folded condition, stringers of hook fasteners mounted longitudinally along the center of the back of said tie over said stitches for hiding said 20 stitches from view and for adding stiffness to said tie, and a control slide for opening and closing said slide fasteners, whereby said slide may be 25 moved to close said fasteners for giving said tie one stiffness and said slide may be moved to open said fasteners to give said tie another stiffness, said fasteners having their stringers attached to said strip on opposite sides of said stitches. 30

DAVID SOBEL.
